UNITED STATES PATENT OFFICE.

FRANCIS G. GALE, OF WATERVILLE, QUEBEC, CANADA.

MATTRESS FRAME.

Application filed November 12, 1921. Serial No. 514,575.

To all whom it may concern:

Be it known that I, FRANCIS G. GALE, a subject of the King of Great Britain, residing at Waterville, Province of Quebec, Dominion of Canada, have invented an Improvement in Mattress Frames, of which the following description, in connection with the accompanying drawing, is a specification, like characters on the drawing representing like parts.

This invention relates to mattress frames and particularly to the corner fastening which is used at the corners of the frame to secure together the side rails and the end rails, and one of the objects of the invention is to provide a novel corner fastening which is made of sheet metal and which is secured to the side and end rails by welding thus avoiding the use of screws, bolts or rivets, and which is also constructed so that it will close the open end of each rail and thus make a sanitary structure which can be easily kept free from vermin.

I accomplish this object by making the corner fastening in two sheet metal sections, one of which is welded to the side rail and is constructed to close the end of the end rail, and the other of which is welded to the end rail and is constructed to close the end of the side rail and both of which are welded together.

In order to give an understanding of the invention I have illustrated in the drawings a selected embodiment thereof which will now be described after which the novel features will be pointed out in the appended claims.

Fig. 1 is a perspective view of a corner of a mattress frame embodying my invention.

Fig. 2 is a section on the line 2-2, Fig. 1.

Fig. 3 is a perspective view of the complete corner fastening with the end rails and side rails removed, said figure showing the corner fastening which is complementary to the fastening shown in Fig. 1.

Figs. 4 and 5 show the blanks from which each corner fastening is made.

Fig. 6 is a perspective view showing the end of the end rail with one section of the fastening secured thereto.

Fig. 7 shows the end of the side rail with the other section of the corner fastening secured thereto.

55 In the drawings 1 indicates the side rail of a mattress frame and 2 the end rail there-

of. Both of these rails are shown as formed from rectangular tubing and the side rail is arranged with its longest transverse dimension in a vertical direction while the end rail 2 is arranged with its longest transverse dimension in a horizontal direction.

The corner fastening by which these two rails are secured together is formed from two sheet metal members indicated at 3 and 4 respectively. The member 4 is shaped to partially embrace the side rail 1 and is constructed so that it can be readily spot welded to the side of the side rail. It is also provided with a portion adapted to close the open end of the end rail when the parts are assembled. The other section 3 is constructed so that it can be readily spot welded to the under side of the end rail 2 and it is provided with a foot portion to rest on the top of the side rail and another portion which closes the open end of the side rail when the parts are assembled. The two sections are constructed so that after they are assembled they can be readily welded together.

The section 4 is herein shown as formed from a blank 5 of sheet metal of the shape shown in Fig. 4 and this is bent along the dotted lines 6 to form the shelf or supporting portion 7 and it is also bent at its upper end along the transverse dotted line 8 to form the flange 9 that is adapted to overlie the top edge of the end rail. The section thus formed comprises the body portion 10 having the two flanges 7 and 9 extending at right angles thereto, the flange 7 constituting a support for the side rail and the flange 9 overlying the top of the end rail. The other section 3 is formed with the body portion 11 adapted to overlie the body portion 10 of the section 4 and which is formed at its lower end with a flange or foot 12 adapted to rest on the top of the side rail 1 and is also formed at its upper end with a transversely-extending flange 13 on which the end rail 2 rests. The member 3 is also formed with the wing portion 14 constructed to close the open end of the side rail 1 when the parts are assembled.

This corner fastening section 3 can conveniently be made from a blank 15 of sheet metal having the shape shown in Fig. 5 and may be formed by bending the blank along the dotted line 16 thereby to form the foot 12 and also bending said blank along the dotted line 17 to form the rest 13. The

blank is further bent along the vertical dotted line 18 to carry the part 14 into a right angular relation to the body of the blank and before this is done the wing portion 19 may be bent into right angular relation along the dotted line 20 so that when the part 14 is bent on the line 18 the part 19 will fold against the body 11 of the blank. The blank is bent along the line 17 after the part 14 is folded so that the portion 13 above the line 17 folds down onto the part 19.

After the two sections have been thus made the section 4 is secured to the side rail 1 by placing the end of the side rail on the rest 7 with the side of the side rail against the body 10 as shown in Fig. 7. The body is then spot welded to the side of the side rail as indicated at 22 and this can be easily done because one leg of the welding tool 20 may be inserted into the open end of the side rail.

The corner fastening section 3 can also be easily welded to the end rail 2 by placing the end rail on the rest 18, as shown in Fig. 6, and then spot welding said rest 18 to the under side of the end rail. This can also be easily accomplished because the end of the end rail is open to permit one leg of the welding tool to be inserted.

After these two sections have been welded to the side rail and end rail, as shown in Figs. 6 and 7, then they are assembled as shown in Figs. 1 and 2 and when in their assembled relation the end of the end rail 35 and the body 11 of the member 3 fit against the upper portion of the body 10 of the member 4, the flange 9 of said member 4 overlies the top of the end rail, the rest 12 of the member 3 rests on the top of the side rail, and the portion 14 of the member 3 closes the end of the side rail. After the

two sections have been thus assembled then the body portion 11 of the section 3 may be spot welded to the upper portion of the member 10 of the section 4 as shown at 23. 45 A corner fastening of this construction is very strong owing to the fact that the body portion 11 has the foot 12 which rests directly on the top of the side rail and thus all the weight on the end rail will be transmitted to the side rail through the body member and not through the spot welding 50 23.

When the corner fastening is completed the ends of both rails are closed thereby 55 making the structure an extremely sanitary one.

I claim.

1. In a mattress frame, the combination 60 with a side rail and an end rail, of a corner fastening connecting said rails and comprising one member rigidly secured to the side rail and having a portion to close the end of the end rail and another section rigidly secured to the end rail and having a portion 65 to close the end of the side rail, said sections being secured together.

2. In a mattress frame, the combination 70 with a tubular side rail and a tubular end rail, of a corner fastening connecting said 75 rails and comprising two sections, one of which overlies and is secured to the side of the side rail and is provided with a flange to overlie the top of the end rail and the other of which is secured to the bottom of the end rail and is provided with a foot to rest on the top of the side rail, the two sections being spot welded together.

In testimony whereof, I have signed my name to this specification.

FRANCIS G. GALE.
